UNITED STATES PATENT OFFICE

KARL KLEINERT, OF STUTTGART, GERMANY, ASSIGNOR TO ROBERT BOSCH
AKTIENGESELLSCHAFT, OF STUTTGART, GERMANY

LAMP FOR VEHICLES

Application filed March 7, 1931, Serial No. 520,921, and in Germany March 15, 1930.

The present invention relates to lamps and more particularly to the mounting of lamps for use with automobile and other vehicles.

5 It is well known to mount vehicle lamps in holders or supports by means of clamps. Generally the clamp is made of two parts and enshrouds a connecting tube fixed to the lamp. This however makes the manu-
10 facture of clamps expensive.

For the purpose of obtaining a securing clamp which is made of two parts, but consists of as few as possible separate elements the present invention provides for
15 a curvated portion on the lamp casing which functions as one part of the clamping yoke.

The present invention is more particularly described by way of example with reference to the accompanying drawing which illus-
20 trates one form of construction and in which:—

Figure 1 is a partial side elevational view of a lamp casing and a partial section through the securing device.

25 Figure 2 is a sectional view on the line AB of Figure 1.

A base flange 2 includes a portion somewhat convex in section as illustrated at 3, this portion having an opening for a lamp sup-
30 port 4. The base 2 is welded or otherwise rigidly secured to a paraboloidal lamp casing 1. One end of an element 5 is riveted to the interior of the casing 1, whilst the other end is adjustably secured to the casing 1 by
35 means of a screw bolt 6. The element 5 together with the convex portion 3 of the base flange 2 together form the yoke in which are disposed two clamping cheeks 7. These cheeks are kept out of engagement
40 with each other by helical springs 8 in order to facilitate the insertion therebetween of the support 4 and together form a cylindri-
cal element having a transverse bore for the support 4.

45 A hole is formed in the element 5 so that a cable for the lamp may be passed through the hollow lamp support 4 and thence through the element and into the lamp cas-
ing.

50 When it is desired to adjust the position

of the lamp relative to its support the clamp-
ing screw 6 is loosened whereupon the lamp and the cheeks 7 are angularly displaced about the vertical axis of the support 4. Further the lamp itself may be swung about
55 the cheeks 7 and support 4 about a horizontal axis. As the lamp need only be inclined upwards or downwards by a small angle when being adjusted, the inclination may be limited in a simple manner by the
60 amount of opening in the lower yoke 3. When the lamp is in the desired position, the yoke 5 is tightened by the clamping screw 6 and the lamp is clamped on the sup-
port 4 by the clamping cheeks 7.

65 Since the securing device is mounted in the interior of the lamp it lies near to the centre of gravity of the lamp which is a desir-
70 irable feature in order to keep the device rigid.

75 If desired, however, the securing device may be mounted on the outside of the cas-
ing as distinct from the form of construc-
tion described in the drawing by way of
example.

I claim:

1. A support for a lamp comprising a tubular member, a convex portion on the casing of the lamp and slotted to receive
80 said tubular member, a clamping member secured to said casing adjacent said convex portion and having a slot formed therein and clamping cheeks between said clamping member and said convex portion for rigidly gripping said tubular member after
85 this has been passed through the slot in said convex portion.

2. A lamp comprising a support, a casing having a convex portion thereof and a slot formed therein, a slotted clamping member rigidly secured to said casing at one end and adjustably secured to the casing at its other end, semi-cylindrical clamping cheeks dis-
90 posed between said clamping member and said convex portion and having a slot formed therein for the reception of said support and means to rigidly engage said support by said clamping cheeks and said clamping cheeks by said clamping member and convex portion in any one of a number
95 100

of positions about vertical and horizontal axes.

3. A lamp comprising a support, a casing having a convex portion thereof and a slot formed therein, a slotted clamping member rigidly secured to said casing at one end and adjustably secured to the casing at its other end, semicylindrical clamping cheeks disposed between said clamping member and said convex portion and having a slot formed therein for the reception of said support, springs normally maintaining said clamping cheeks apart and means to rigidly engage said support by said clamping cheeks and said clamping cheeks by said clamping member and convex portion in any one of a number of positions about vertical and horizontal axes.

In testimony whereof I have hereunto affixed my signature.

KARL KLEINERT.
